CLAIM

The ornamental design for a ring holder, as shown and described.

DESCRIPTION

FIG. 1 is an upper right perspective view of a first embodiment of a ring holder showing my new design;

FIG. 2 is a top plan view thereof;

FIG. 3 is bottom plan view thereof;

FIG. 4 is a right side elevational view thereof; The right side elevational view being a mirror image of the right side elevational view;

FIG. 5 is an upper right perspective view of a second embodiment of a right holder showing my new design;

FIG. 6 is a top plan view of the second embodiment;

FIG. 7 is bottom plan view of the second embodiment; and, FIG. 8 is a right side elevational view of the second embodiment; The left side elevation view being a mirror image of the right side elevational view.
